TOY JACK-IN-THE-BOX

Anthony B. Laganella, 1824 Dudley St., and Charles E.
McMenamin, 554 Acorn St., both of Philadelphia, Pa.

Filed Nov. 2, 1959, Ser. No. 58,159

Term of patent 14 years

(Cl. D34—15)

FIG. 1

FIG. 2

FIG. 3

FIG. 4

FIG. 5

FIG. 6

The box cover is omitted in Figures 1 to 4, all showing the box in open position for convenience of illustration.

We claim:

The ornamental design for a toy jack-in-the-box, as shown and described.
